UNITED STATES PATENT OFFICE.

ROBERT TOLSON, OF WASHINGTON, DISTRICT OF COLUMBIA.

GRAIN-STORING APPARATUS.

No. 894,085.

Specification of Letters Patent.

Patented July 21, 1908.

Application filed April 2, 1908. Serial No. 424,811.

To all whom it may concern:

Be it known that I, ROBERT TOLSON, of Washington, District of Columbia, have invented a new and useful Improvement in 5 Grain - Storing Apparatus, which improvement is fully set forth in the following specification.

This invention relates to means for transporting corn and other grains from the 10 wagon in which the same is brought from the field and depositing it in a corn-crib or other granary designed for its reception.

The object of the invention is to provide 15 strong, simple and efficient means that may be operated by suitable power ordinarily found on a farm, and preferably by horse-power, and consists, generally speaking, in an inclined track or way leading from a suitable point outside of the corn-crib or granary 20 to within the granary, upon which track or way there is mounted a suitable car provided with a hinged bottom. This bottom is provided with a spring or other device for automatically closing the door or bottom in the 25 absence of any weight thereon, but which spring or automatic closing device would yield under the weight of the load to permit the door or bottom to open and the contained load of grain to drop through the bottom. For the purpose of preventing the 30 bottom from thus opening under the influence of the load except at the desired time, a suitable catch or catches is or are provided to retain the door in its closed position, and an 35 adjustable stop or abutment is secured in a suitable position, and preferably on the track or way within the corn-crib or granary, for actuating the catch to free the bottom when the car is advanced to the position where it is 40 desired to deposit the load contained therein.

Preferably this tripping action is secured by the advancement of the car in to a position to cause the catch to impinge upon the stop and move it against the tension of a spring to 45 trip the catch, whereupon the bottom or door of the car swings open under the influence of the weight of the grain contained therein, and the grain having fallen from the car, the spring returns the bottom or door to 50 its closed position, and the power which is applied to the car to bring it into trip position having been eased or released, the catch immediately returns to retaining position.

The invention may assume various mechanical forms, one of which, for the sake of description, is shown in the accompanying drawings, in which—

Figure 1 is a part elevational, part sectional view, showing the track or way with a car thereon, and the manner in which it is advanced into the corn-crib or granary; Fig. 2 is a bottom plan view of the car; Fig. 3 is a perspective view of the car slightly tilted up so as to afford a view of the bottom and walls thereof; and Fig. 4 is a detail of one 60 form of adjustable stop device which may be employed.

Referring to the drawings, 1 is a corn-crib or granary, and 2 is a track or way leading from a point 3, here shown as approximately 65 on the ground level, up into the corn-crib or granary which is provided with a side door or opening 4. Mounted on the track or way is a car 5, preferably of hopper shape, which has a bottom 6 hinged at 7, 7, to the car, the hinge straps 8, 8, preferably extending entirely across the bottom of the car to strengthen the same. Reacting between the body of the car and the door 6 is a spring 9, which in the absence of any load 70 within the car acts to hold the door constituting the bottom of the car in closed position. Suitably mounted on the car is a catch for engaging the door 6 and holding it in closed position even when the car is loaded. 75 As here shown, this catch takes the form of a square rod 10 so mounted on the car that it cannot turn. At its rear end 11 this rod bears against a spring 12, and its forward end 13 projects out beyond the bottom of the car, 80 as will be clearly understood from an inspection of Figs. 2 and 3.

Suitably positioned within the corn-crib or granary 1 is a stop or abutment 14 which lies in the path of the forward end 13 of the 85 stop 10 when the car is advanced into dumping position within the granary. This stop may be mounted upon any suitable support, and is here shown as mounted upon the track or way 2, and in order that the dumping 90 action of the car may be secured at any desired point within the granary this stop or abutment 14 is made adjustable, as clearly shown in Fig. 4, the adjustment being secured in this instance by providing a long 95 slot 15 in the metal bar of which the abutment, in this instance, is made, and the stop being secured to the track or way by clamping nuts or screws 16, 16. It will be apparent that by loosening the said clamping nuts 100 or screws, the stop may be adjusted along the track as desired.

Any suitable power may be employed for advancing the car up and down the way, and

as here shown a cable 17 is secured to the car and passed over a pulley 18 within the corn-crib or granary, and thence returned to a pulley 19, and from thence to the source of power, as, for example, to a horse. It will of course be understood that in passing the cable 17 from the pulley 18 to the pulley 19, it must be deflected in a suitable way, so as not to interfere with the dumping action of 10 the door 6.

The operation of the device is as follows:— The position of the car being such that a wagon 20 may be backed up close to the car, the corn or other grain is shoveled from the 15 wagon into the car, and then through the cable 17 power is applied to elevate the car along the track or way until it enters the corn-crib or granary through the door 4, and, the projecting end 13 of the catch bar 10, 20 striking against the abutment 14, pushes the said catch bar 10 rearward against the tension of its spring 12. This action shifts the catch lugs 21, 21, formed on said bar from off the hinge straps 8, 8, opposite to cut-away 25 openings 22, 22, in the door, and the weight of the load upon the door swings it open against the tension of the spring 9, when the hopper-like shape of the car permits all of the corn or other grain to be instantly dumped 30 into the corn-crib or granary. The weight being removed from the door, spring 9 returns the door to its closed position, the car having been held so as to force the forward end 13 of the catch bar 10 tightly against the 35 stop 14. When the car door is returned to its closed position by the spring, the lugs 21 on the catch bar will be opposite the openings 22 and the door will readily close. At this point the tension on the cable 17 is eased, 40 as by backing the horse slightly, and the catch bar is then automatically pushed forward by the spring 12, so that the lugs 21, 21, again advance under and engage the hinged straps 8, 8. The car is then permitted to 45 return by gravity to its normal position behind the wagon, and the operation is repeated.

What I claim is:—

1. The combination with a corn-crib or 50 granary, of an inclined track or way extending from without to within said crib or granary, a car mounted on said track or way, a hinged bottom to said car, a catch device normally holding the door closed against the 55 tendency of the weight of material in the car to open the door, means located within the crib or granary automatically tripping said catch device whereby the door is permitted to swing open under the weight of the contained load, and means automatically closing 60 said door when the load has been dumped.

2. The combination with a crib or granary, 65 of an inclined track or way passing from a point without to a point within said crib or

granary, a car on said way, a hinged bottom 65 to said car, a spring acting to close said bottom in the absence of any load in the car, a catch normally engaging the door and holding it in its closed position against the weight of the contained load, and a stop located 70 within the crib or granary automatically tripping said catch, whereby the load will be automatically dumped within the crib or granary and the door automatically closed and reengaged by the catch. 75

3. The combination with a crib or granary, of an inclined track or way extending from a point without to a point within said crib or granary, a hinged bottom to said car, a spring reacting on said bottom so as to close 80 the same in the absence of any load in the car, a catch bar mounted on the side of the car 85 and having parts engaging the door to hold the same closed against its contained load and having a projecting part, a spring normally acting on said catch bar to hold said lugs in engagement with the door, and an adjustable stop mounted within said crib or granary in the path of said projecting part whereby when the car is advanced to the desired dumping point within the crib or granary, said stop serves to actuate said catch bar and trip the catch against the tension of its spring, the door is opened under the weight of the contained load, which being dumped, is then closed by said door spring, and the catch is returned by its spring to its normal engaging position with the door. 95

4. The combination with a crib or granary, of an inclined track or way extending from a point without to a point within said crib or granary, a hinged bottom to said car, a spring reacting on said bottom so as to close 100 the same in the absence of any load in the car, a catch bar mounted on the side of the car 105 and having parts engaging the door to hold the same closed against its contained load and having a projecting part, a spring normally acting on said catch bar to hold said lugs in engagement with the door, and a stop mounted within said crib or granary in the path of said projecting part, whereby when the car is advanced to the desired dumping point within the crib or granary, said stop serves to actuate said catch bar and trip the catch against the tension of its spring, the door is opened under the weight of the contained load, which being dumped, is then closed by said door spring, and the catch is returned by its spring to its normal engaging position with the door. 110

In testimony whereof I have signed this specification in the presence of two subscribing witnesses.

ROBERT TOLSON.
